UNITED STATES PATENT OFFICE.

WILLIAM R. STUCK, OF LOS ANGELES, CALIFORNIA, ASSIGNOR TO DAZEY MANUFACTURING COMPANY, OF LOS ANGELES, CALIFORNIA, A CORPORATION OF CALIFORNIA.

DESIGN FOR A FLOWER-BOWL STAND.

Application filed February 10, 1923. Serial No. 5,144. Term of patent 3½ years.

To all whom it may concern:

Be it known that I, WILLIAM R. STUCK, a citizen of the United States, residing at Los Angeles, in the county of Los Angeles and State of California, have invented a new, original, and ornamental Design for Flower-Bowl Stand, of which the following is a specification, reference being had to the accompanying drawing, forming part thereof.

I claim:

The ornamental design for a flower bowl stand.

Signed at Los Angeles, California, this 11th day of January 1923.

WILLIAM R. STUCK.
